US0D1079772S

(12) **United States Design Patent** (10) **Patent No.:** **US D1,079,772 S**
(45) **Date of Patent:** **** Jun. 17, 2025**

(54) **PROCESS ROLL**

(71) Applicants: **David S. Hoover**, Curtiss, WI (US);
Loren Shirk, Colby, WI (US)

(72) Inventors: **David S. Hoover**, Curtiss, WI (US);
Loren Shirk, Colby, WI (US)

(**) Term: **15 Years**

(21) Appl. No.: **29/855,991**

(22) Filed: **Oct. 10, 2022**

(51) **LOC (15) Cl.** **15-03**

(52) **U.S. Cl.**

USPC **D15/138; D15/28**

(58) **Field of Classification Search**

USPC D15/10, 11, 28, 29, 131, 138, 139;
D7/372, 414

CPC . B02C 17/20; B02C 19/0012; B02C 19/0018;
B02C 19/0025; B02C 21/00; B02C 21/02;
B02C 4/00; B02C 4/30

(57) **CLAIM**

The ornamental design for a process roll, substantially as shown and described.

DESCRIPTION

FIG. 1 is a perspective view of a process roll, showing our new design;

FIG. 2 is a front view of the process roll of FIG. 1;
FIG. 3 is a rear view of the process roll of FIG. 1;
FIG. 4 is a top view of the process roll of FIG. 1;
FIG. 5 is a bottom view of the process roll of FIG. 1;
FIG. 6 is a right side view of the process roll of FIG. 1; and,
FIG. 7 is a left side view of the process roll of FIG. 1.

1 Claim, 4 Drawing Sheets
